UNITED STATES PATENT OFFICE.

JOHN C. POORE, OF CHICAGO, ILLINOIS.

NIPPLE FOR NURSING-BOTTLES.

1,095,969.

Specification of Letters Patent.

Patented May 5, 1914.

Application filed April 18, 1911. Serial No. 621,879.

To all whom it may concern:

Be it known that I, JOHN C. POORE, a citizen of the United States, residing at Chicago, in the county of Cook and State of Illinois, have invented certain new and useful Improvements in Nipples for Nursing-Bottles, of which the following is a specification.

This device consists of a teat telescoping upon itself and having its free end projecting outwardly to form a nipple, the teat being usually formed with an air inlet arranged to open into the space between the opposing walls of the telescoping portions, and one of said opposing walls having an annular flange which projects toward and engages the other of said opposing walls and acts as means for preventing outflow through the opening.

20 This invention relates to improvements in teats or nipples for nursing bottles and has for its object to provide a nipple so constructed that it will admit air into a bottle as liquid is being withdrawn therefrom.

25 With the above and other objects in view, I have invented the nipple illustrated in the accompanying drawings, in which,

Figure 1 is a longitudinal sectional view of a bottle and my improved nipple, Fig. 2 is a vertical sectional view of a nipple removed from the bottle and shown collapsed, Fig. 3 is a vertical sectional view of a modified form of the nipple, Fig. 4 is a top plan view of Figs. 1 and 2, Fig. 5 is an elevational view of the nipple straightened out, Fig. 6 is a longitudinal sectional view through a modified form of the invention, Fig. 7 is an elevational view of Fig. 6, the nipple end being removed, and Fig. 8 shows 40 a vertical sectional view of the modified form attached to a bottle.

Referring to the accompanying drawings 1 indicates a flexible nipple provided with an opening 2 in its end 3. Extending upward from the lowermost portion 4 of the nipple is a collar 5 which is provided with an overlapping portion 6 which is adapted to slip over the rim 7 and upper portion 8 of the crucible shaped bottle 9 thereby holding 50 the nipple securely onto the bottle.

On the portion 5 is a circumferential flange 10 extending toward the nipple proper, its outer edge 11 normally contacting same entirely therearound, the flange 55 remaining always in a fixed position as indi-

cated in Figs. 1 and 2. The nipple and the flange are so formed that a space 12 is left therebetween and apertures 13 and 14 are provided in the lower portion 4 connecting with the space 12 whereby air may enter 60 said bottle at the moment the nipple is collapsed in sucking milk from the bottle. The nipple being pressed away from the edge 11 of the flange as shown in Fig. 2 permits the air to enter the space 12. When the 65 hold on the nipple is released it again engages the flange and closes the opening 14 into the space 12.

In Fig. 3 I show a modified form of the invention in which two nipple engaging 70 flanges 15 and 16 are provided whereby an extra precaution is taken to prevent any liquid from passing from the inside of the bottle through the apertures 13 and 14 to the outside of the nipple. By using a nipple 75 of this construction an infant is saved from wind colic as it is prevented from sucking wind into its stomach in its effort to suck milk from a collapsed nipple as this nipple will never remain collapsed when pressure 80 thereagainst is removed the air entering the bottle through the apertures 13 and 14 being sufficient to compensate for the milk withdrawn from the bottle, thus no vacuum is formed in the bottle to hold the nipple collapsed.

In Figs. 6, 7, and 8 I show another modified form of the invention in which the member 17 has an opening 18 in its upper part and is provided with a rim 19 around said 90 opening whereby an ordinary nipple may be secured thereto; otherwise the device is the same as that above described.

This improved nipple is very sanitary as it may be straightened out for cleansing as 95 shown in Figs. 5, 6, and 7, and being flexible may be readily turned inside out for washing.

I claim and desire to secure by Letters Patent,

1. A teat for nursing bottles, the teat comprising a collapsible nipple having an outlet opening at its free end, the teat also being formed with an inlet for air, and means operated by the collapsing action of 105 the nipple for permitting air to pass through the inlet, substantially as and for the purpose described.

2. A teat for nursing bottles, the teat comprising a collapsible nipple having an 110

- outlet opening, an air inlet opening, and external means for controlling the flow of air through the latter opening, said means normally engaging the periphery of the nipple, and portions of the nipple being movable out of engagement with said means during the collapsing of the nipple and thereby permitting the inflow of the air, substantially as and for the purpose specified.
3. A teat for nursing bottles, the teat comprising a collapsible nipple having an outlet opening, an air inlet opening, and an exterior annular flange normally engaging the periphery of the nipple above the air inlet opening and thus preventing the air from entering through such inlet opening, portions of the nipple moving out of engagement with the annular flange during the collapsing of the nipple and thereby permitting the air to enter the inlet opening and fill the partial vacuum within the nipple, substantially as and for the purpose set forth.
4. A teat for nursing bottles comprising a collapsible nipple having an outlet opening, the teat also having an air inlet opening and means coacting with the nipple for normally closing the air inlet opening, portions of the nipple being movable out of engagement with said means during the collapsing of the nipple, and thereby opening the air inlet opening, substantially as and for the purpose described.
5. A teat for nursing bottles comprising a collapsible nipple having an outlet opening, at its free end, the teat also having an air inlet opening near the inner end of the nipple, the teat being also formed with a flange normally engaging the periphery of the nipple above the air inlet opening, portions of the nipple being movable out of engagement with the flange during the collapsing of the nipple and thereby permitting the air to enter the air inlet opening, and fill the collapsing nipple, substantially as and for the purpose specified.
6. A teat for nursing bottles, the teat being telescopic upon itself, and the inner portion thereof constituting a nipple, and having an outlet opening at its free end, and the teat being formed with an inlet for air, opening into the space between outer and inner portions thereof when the teat is telescoped upon itself, and one of said portions being provided with means projecting across such space and engaging the other portion to control the passage of air in said inlet, substantially as and for the purpose set forth.
7. A teat for nursing bottles, the teat being telescopic upon itself, and the inner portion thereof constituting a nipple, and having an outlet opening at its free end, and the teat being formed with an inlet

for air, opening into the space between outer and inner portions thereof when the teat is telescoped upon itself, and one of said portions being provided with an annular flange projecting across such space and engaging the other portion for controlling the passage of air in said inlet, substantially as and for the purpose described.

8. A teat for nursing bottles, the teat being telescopic upon itself, and the inner portion thereof constituting a nipple and having an outlet opening at its free end, and the teat being also formed with an inlet for air opening into the space between outer and inner portions thereof when the teat is telescoped upon itself, and the outer portion being provided with means projecting into such space to control the passage of air in said inlet, substantially as and for the purpose specified.

9. A teat for nursing bottles, the teat being telescopic upon itself, and the inner portion thereof constituting a collapsible nipple having an outlet opening at its free end, and the teat being formed with an inlet for air opening into the space between outer and inner portions thereof when the teat is telescoped upon itself, and the outer portion being provided with an annular flange engaging the periphery of the nipple and arranged to normally close the entrance to said space, substantially as and for the purpose set forth.

10. A teat being telescopic upon itself, and having a free end projecting outwardly to form a nipple, the walls of said teat having openings therethrough, means for preventing an outflow through said openings, said means consisting of an annular flange projecting upwardly when said teat is telescoped, and having its free edge normally engaging the wall of said nipple.

11. A teat being telescopic upon itself, and having a free end projecting outwardly to form a nipple, the walls of said teat having openings therethrough, means for preventing an outflow through said openings, said means consisting of an annular flange projecting upwardly when said teat is telescoped, and having its free edge normally engaging the wall of said nipple, said flange maintaining a rigid position relative to said nipple.

12. A teat having openings through the walls thereof, an inclined flange below the line of said openings, said teat adapted to be bent upon itself so that said flange will contact said wall above said openings.

13. A teat telescoping upon itself and having its free end projecting outwardly to form a nipple, substantially as and for the purpose described.

14. A teat telescoping upon itself whereby opposing walls are formed, the inner portion of the teat extending beyond the outer

portion and forming a nipple, the teat being formed with an air inlet arranged to open into the space between said walls from the interior of the nipple, substantially as and for the purpose specified.

15. A teat telescopic upon itself and having its free end projecting outwardly to form a nipple, the walls of the teat having an opening which opens into the space 10 between the telescopic portions from the interior of the teat, substantially as and for the purpose set forth.

16. A teat telescopic upon itself and having its free end projecting outwardly to 15 form a nipple, the walls of the teat having an opening which opens into the space between the telescopic portions from the interior of the teat, and means for preventing outflow through the opening, substantially 20 as and for the purpose described.

17. A teat telescopic upon itself and having its free end projecting outwardly to form a nipple, the walls of the teat having an opening which opens into the space 25 between the telescopic portions from the interior of the nipple, and means for preventing outflow through the opening, said means including an annular flange carried by one of the telescopic portions and engaging the 30 other of said portions, substantially as and for the purpose specified.

18. A teat including telescopic portions, the inner portion projecting beyond the outer portion and forming a nipple and a 35 flange provided on one of said portions and extending toward the other to normally close the space between the inner and outer por-

tions, substantially as and for the purpose set forth.

19. A teat including telescopic portions, 40 the inner portion projecting beyond the outer portion and forming a nipple, and a flange provided on the outer telescoping portion and arranged to extend toward the inner portion and engage the periphery of 45 the same, substantially as and for the purpose described.

20. A teat including telescopic portions, the inner portion projecting beyond the outer portion and forming a nipple, and a 50 flange provided on the outer telescoping portion and arranged to extend toward the inner portion and engage the periphery of the same, the flange inclining upwardly, substantially as and for the purpose specified. 55

21. A teat including telescoping portions, the inner portion projecting beyond the outer portion and forming a nipple, and a flange provided on the outer telescoping portion and arranged to extend toward the 60 inner portion and engage the periphery of the same, the flange inclining upwardly, the nipple being formed with a passage opening into the space between its inner and outer portions from the interior of the teat, 65 the opening being located below the flange, substantially as and for the purpose set forth.

In testimony whereof I affix my signature in presence of two witnesses.

JOHN C. POORE.
